UNITED STATES PATENT OFFICE.

EDWARD N. CRANE, OF NEWARK, NEW JERSEY.

DESIGN FOR HARNESS-TRIMMING.

SPECIFICATION forming part of Design No. 13,562, dated January 30, 1883.

Application filed October 24, 1882. Term of patent 14 years.

To all whom it may concern:

Be it known that I, EDWARD N. CRANE, of the city of Newark, in the county of Essex and State of New Jersey, have originated and invented a new and useful Design for Harness-Trimming; and I do hereby declare that the following is a full, clear, and exact description thereof, reference being had to the accompanying drawings, forming a part of this specification, in which—

Figure 1 is a side elevation of a terret and an edge view of the same. Fig. 2 is a side elevation and edge view of a hook. Fig. 3 is a front view of a buckle and a side view of the same. Fig. 4 shows another style of chain. These are representative articles of solid hardware-trimmings, and all the parts of the harness-trimmings will be ornamented after the same pattern.

The chief feature of my design is the chain, either plain, twisted, or other form, running

through a broad band upon the flat surface of the trimmings, but forming a part of the same, the chain being inlaid upon the band. The chain is to be of some contrasting color with the band. It may be formed of enamel or inlaying composition, or it may be formed of any metal the color of which will contrast with the band. Thus any dark and light metal may be combined, or a white and a yellow metal, or any combination of metals and enamels of different colors which will bring out the design of a chain on a band of any color.

I claim—

The terret, hook, or other harness-trimming having the exterior ornamented with a chain running through a broad band upon the surface thereof, substantially as set forth.

EDWD. N. CRANE.
